ELEVATOR CONTROL

Carroll Stansbury, Wauwatosa, and Glendon C. Brown, Milwaukee, Wis., assignors to Cutler-Hammer, Inc., Milwaukee, Wis., a corporation of Delaware

Application May 21, 1931. Serial No. 539,114

13 Claims. (Cl. 175—294)

This invention relates to electronic control means which is particularly advantageous for elevator control although not limited to such application.

5 An object of the invention is to provide for elevator control and other uses electronic means for introducing a definite time interval between successive operations of a controlled translating device such for example as the driving motor of an elevator.

10 Another object is to provide an improved elevator control system including phase failure and phase reversal protection and protection against premature starting of the elevator after stoppage thereof to afford passengers sufficient time to enter and leave the elevator.

15 Another object is to provide means for controlling the current flow through a gaseous electron tube in such a manner that after it has been stopped, it is prevented from immediately starting again upon re-establishment of circuit connections by a negative grid potential which is made to persist for a given time.

Another object is to provide means for introducing a definite minimum time interval between successive operating periods of an electron tube, and means to eliminate such time interval at will.

20 Another object is to provide in an alternating current system for combined phase failure and phase reversal protection, including means for introducing a time delay in the current flow upon re-establishment of current supply after interruption thereof.

25 35 Other objects and advantages will hereinafter appear.

The accompanying drawings illustrate an embodiment of the invention. In the drawings

Figure 1 is an elementary diagram illustrating use of the invention to delay the re-establishment of current flow through a gaseous electron tube for a given time after interruption thereof.

Fig. 2 shows the application of the system illustrated in Fig. 1 in combination with a phase failure and phase reversal protective system for a three-phase circuit, while

Fig. 3 illustrates the system of Fig. 2 as applied to an elevator driven by a polyphase motor and providing for phase failure, phase reversal and non-interference protection.

Referring to Fig. 1, L^1 and L^2 are respectively the positive and negative lines of a direct current supply system, 1 is a gaseous electron tube

5 having a cathode 2, an anode 3 and a grid 4. An electromagnetic switch 5 is provided with an energizing winding 6, normally open main contacts 7, normally closed auxiliary contacts 8 and normally open auxiliary contacts 9. The system also includes a condenser 10 having plates 60 of opposite polarity 11 and 12. In circuit with the plate 12 and one of the contacts 8 may be a resistance 13, while another resistance 14 is connected between plate 11 and the other of said contacts 8, which latter is also connected 65 through a resistance 15 to the grid 4. A translating device 16, the current of which is to be controlled, is connected between the cathode 2 and one of the normally open contacts 7, while the other of said contacts is connected to line 70 L^2 . The winding 6 is connected in series with a normally open push button switch 17 between the line L^2 and the cathode 2, the latter also being connected to the condenser plate 11, while the anode 3 is connected to line L^1 . The system 75 illustrated in Fig. 1 functions in the following manner:

When the lines are deenergized, the grid 4 is substantially at the potential of the cathode 2. With the lines energized and the push button 80 17 depressed, circuit is closed from the line L^1 to anode 3, cathode 2, push button 17, coil 6, to line L^2 . The switch 5 is thus energized, thereby opening contacts 8 and closing contacts 7 and 9.

Closure of contacts 7 connects the translating 85 device in series with the tube 1, thereby supplying current to the former, while closure of contact 9 impresses upon the plate 12 of the condenser the potential of line L^2 , which is negative with respect to the cathode 2 by an 90 amount, which is the difference of the potential of lines L^1 and L^2 and the voltage drop in the tube 1.

The plate 11 of the condenser accumulates a corresponding positive charge. If now the push button switch 17 is released, the magnet 95 switch 5 is deenergized, thereby opening contacts 7 and 9 and closing contacts 8. The current flowing through the translating device 16 through contact 7 is thus interrupted and the charge of the condenser 10 is terminated by the 100 opening of the contacts 9. The simultaneous closing of contacts 8 connects condenser plate 12 to the grid 4 and thus impresses thereon a potential negative with respect to the cathode, while simultaneously a discharge circuit is completed from condenser plate 11 through resistance 14, contacts 8, resistance 13 to plate 12.

105 The negative charge of the condenser plate 12 is thus gradually reduced by the discharge current, until ultimately the grid again reaches a 110

potential which will permit current flow through the tube 1 if the push button 17 is depressed. The time when this takes place depends upon the impedance of the resistances 13 and 14. 5 Therefore, if the push button switch 17 is depressed prematurely, the grid has still a negative potential sufficient to prevent current flow through the tube 1 and current supply to the translating device 16 cannot be re-established 10 until the negative potential of condenser plate 12 and of the grid has been sufficiently lowered. 15 The system illustrated in Fig. 1 may also be used when the supply of current is alternating. In this case, the operation is substantially the same as described heretofore except that current flows through the tube 1, the electromagnetic winding 6 and the translating device 16 only during alternate half cycles when the cathode 2 and line L^2 are negative with respect 20 to anode 3 and line L^1 . Also the charging of condenser 10 proceeds only during alternate half cycles when the cathode 2 is negative with respect to anode 3. In order to avoid the complete discharge of the condenser 10 during alternate half cycles, in case of alternating current supply, there is provided in series with the plate 12, the resistance 13 which assures that only part of the charge impressed upon the condenser 10 during one of the charging half cycles 25 is again discharged during the alternate half cycle.

In order to smooth out the current fluctuations due to the alternating voltage in the coil 6 and translating device 16, it may be desirable in 30 some cases to connect a rectifier 18 between the cathode 2 and the line L^2 . This rectifier may be of any well known type and its effect in smoothing out the current supply to any translating device in series with the tube 1 is well known to those skilled in the art. 40

Fig. 2 shows the application of the system of Fig. 1 in combination with a phase failure and phase reversal protective system for a polyphase circuit such as described in the application by 45 Carroll Stansbury and Glendon C. Brown, Serial No. 432,278, filed February 28, 1930. However, the invention may be used in combination with other phase failure and phase reversal protective systems. In the system which is disclosed in the aforementioned application, the current supply to a translating device is controlled by an electron tube and conduction through the latter is dependent upon normal 50 conditions of voltages and phase relation of the supply. To apply the present invention to such a system, the grid of the electron tube is influenced by the time delay feature involved in the present invention, so that in addition to preventing current flow through the tube when 55 conditions of current supply are abnormal, the tube is also prevented from re-establishment of current flow to the translating device for a given interval after interruption of such flow by the regular control instrumentalities.

60 Besides the elements of Fig. 1 which are indicated by like numerals in Fig. 2, the latter has additional elements which are described in the following: Three supply lines L^1 , L^2 and L^3 supply polyphase current of suitable voltage. Connected between the lines L^1 and L^2 is a primary winding 23 of a transformer having a secondary winding 24. The winding 23 is provided with a mid-tap between which and the line L^3 is connected the primary winding 21 of a second transformer 70 20, having a secondary winding 22. The

system further includes a normally open triple contact push button switch 19. Two of the contacts of the latter are respectively connected in parallel with the two contacts of push button switch 17, while the third contact of push button switch 19 is connected to one of the contacts 8 which connects to resistance 15. It will be observed that with respect to the current supplied for the winding 6 and the translating device 16, the center tap corresponds to the line L^2 of Fig. 1. The grid 4 is connected in series with windings 24 and 22 and through the resistance 15 to one of the normally closed auxiliary contacts 8. All other connections are similar to those of Fig. 1. 80 85 90

In case of phase failure or phase reversal, the voltage impressed upon the grid 4 is of such value and has such phase relation with respect to the voltage impressed upon the main electrodes 2 and 3, as to prevent current flow through the tube and it therefore prevents current flow to the electromagnetic switch 5 and the translating device 16. The functioning of this part of the system is fully described in the above-mentioned co-pending application. 95 Thus, upon abnormal conditions obtaining in the current supply, no current can flow through winding 6 of the electromagnetic switch 5 and therefore no current can be supplied to the translating device 16. 100 105

However, when normal conditions exist in the system and the push button switch 17 is depressed the coil 6 is energized so that the electromagnetic switch 5 closes the circuit of the translating device 16 and current is supplied thereto in the manner already described. At the same time the condenser 10 is charged in the aforescribed manner and upon release of the push button switch 17 a negative potential is impressed upon the grid 4 which prevents re-establishment of current flow through the tube upon reclosure of the push button switch 17 until the condenser has been discharged as has been explained. 110 115 120

Push button switch 19 is provided to eliminate, 120 when depressed, the time delay effect of the condenser 10 upon the current flow in the tube 1. It will be noted that upon closure of switch 19, a circuit is completed from condenser plate 11 through said switch, through contacts 8 and 125 resistance 13 to condenser plate 12 and another circuit is closed from cathode 2, through switch 19, resistance 15, windings 22 and 24, to grid 4. Thus the grid potential at the moment of depression of the button 19 is determined solely 130 by the drop in resistance 15 and the voltages induced in the windings 22 and 24 and if the conditions of current supply are normal, the tube will immediately conduct current, thus permitting energization of winding 6 and current 135 supply to the translating device 16. It is thus apparent that by the selective use of push button switches 19 and 17 current supply to the translating device 16 and the winding 6 of the electromagnetic switch is controlled to respond 140 either immediately or after a given time delay from the moment of previous interruption upon the depression of the respective button, the current supply being further responsive at all times to conditions of voltage, phase rotation and 145 phase continuity of the source of supply.

Referring now to Fig. 3, the system comprises the polyphase supply lines L^1 , L^2 and L^3 to which are connected in the aforescribed manner, an electron tube 1, transformer primaries 21 and 150

23 having respectively secondary windings 22 and 24, and a rectifier 18. The electron tube 1 supplies rectified current for the various control instrumentalities of the system. An alternating current motor 25 operates an elevator cage 26. The current through the motor is controlled by a pair of electromagnetic reversing switches 27 and 28, having normally open main contacts 27^a and 27^b and 28^a and 28^b respectively, and normally open auxiliary contacts 27^c and 28^c respectively. Geared or otherwise connected to the motor is a commutator 29 having rotating segments 29^a and 29^b and stationary contacts 29^c to 29^e, inclusive, which stationary contacts engage one or the other segment as the motor rotates and the elevator car occupies various positions in the hatchway. An electromagnetic relay 30 has a winding 30^a, normally open contacts 30^b and normally closed contacts 30^c, these latter contacts corresponding respectively to the contacts 9 and 8 of Fig. 2. Mounted in the elevator cage are push button switches 31, 32 and 33 corresponding to the three floors of the elevator hatchway. 25 These push button switches have respectively normally closed contacts 31^a, 32^a and 33^a and normally open triple contacts 31^b, 32^b and 33^b. Mounted on the floors adjacent to the hatchway doors are the push buttons 34, 35 and 36, one 30 on each floor,—these push buttons having normally closed contacts 34^a and 35^a and normally open contacts 34^b, 35^b and 36^b. At each landing door are also mounted the normally open hatchway switches 37, 38 and 39, these switches 35 being closed when the hatchway door is closed. A similar switch 40 is connected to the door of the elevator cage, and a normally closed stop button 41 is also mounted on the inside of the elevator cage. The switches 37 to 41, inclusive, 40 are all connected in series and in series with the magnet coils of the switches 27, 28, so as to prevent energization of the latter if any one of them should be opened.

For the several floors are provided relays 42, 45 43 and 44, respectively, having magnet windings 42^a, 43^a and 44^a, respectively and two pair of normally open contacts 42^b, 42^c; 43^b, 43^c; 44^b and 44^c, respectively.

The system operates as follows: Assuming 50 that the elevator is at the second floor and a passenger has entered and wishes to proceed to the third floor, he closes the elevator door, thereby closing switch 40 and pushes button 31. This closes circuit from line L¹ through tube 1 and from cathode 2 thereof over the normally closed contacts of push buttons 33 and 32 to the center contact of normally open contacts of push button 31, through winding 42^a over switches 40, 41, 37, 38 and 39 to line L², and if 55 the grid 4 does not have too high a negative potential with respect to the cathode 2, tube 1 becomes conducting and relay 42 is energized, thereby closing its normally open contacts 42^b and 42^c. Closure of contact 42^c closes a circuit from cathode 2 through contact 42^c to contact 29^d, over segment 29^a to contact 29^c, through the coil of magnet switch 27, through contacts 40, 41, 37, 38 and 39 to line L². Switch 27 is thereby energized and this closes the circuit to the motor. Closure of contact 27^c also completes a circuit from cathode 2 to contact 42^b through coil 42^a through contacts 40, 41, 37, 38 and 39 to line L². The relay 42 will thus remain closed if the push button 31 is released and it will 75 also keep closed the electromagnetic switch 27

and maintain the motor energized and cause the elevator to rise to the third floor.

When the third floor is reached, contact 29^d breaks with the segment 29^a. This opens the current supply to the switch 27 and disconnects 80 the motor. In opening, switch 27 opens contact 27^c thereby opening the supply of current to the coil 42^a and causing the relay 42 to open. If during the travel of the elevator, the stop button 41 should be pressed by the occupant of the car or any of the switches 37, 38, 39 or 40 are opened, the current supply to the switch 27 is opened and the elevator is stopped.

When the switch 27 closes, its contact 27^c also closes a circuit for relay 30 as follows: From cathode 2 over left-hand contact 27^c through the bridging piece thereof through coil 30^a to line L². The relay 30 is thus energized as long as the switch 27 is energized. When relay 30 is energized the contacts 30^b are closed and contacts 30^c are 95 opened. A negative potential is thus impressed upon plate 12 of the condenser 10 in the manner aforescribed in connection with Fig. 1, and if the switch 27 opens and contacts 30^c close, this negative potential is impressed upon the grid 100 circuit, thus making the grid negative with respect to the cathode for a limited time and preventing the tube 1 from conducting current. Therefore, if one of the push buttons 34, 35 or 36 should be depressed at the moment when the 105 elevator comes to a stop at a floor, current would not be supplied to the controlling mechanism for an interval which permits the occupant of the car to open the door and step out. The opening of the door, of course, opens the safety switches 110 aforescribed and thereby eliminates the effect of the depression of any one of the push buttons until such switches are closed again by the closure of the corresponding door.

The time delay is only effective to cause a delay with respect to the landing push buttons 34, 35 and 36 and is not effective with respect to the car push buttons 31, 32 and 33, because the latter push buttons are arranged to short circuit 120 the condenser and its discharge resistance so that no potential is impressed on the grid by the condenser in the manner aforescribed.

If it is desired to have the elevator car move in the opposite direction to that described, a corresponding push button is pressed and the 125 switch 28 is energized thereby reversing two of the motor connections and causing it to reverse, the operation of the various relays and contacts being the same as that of the corresponding relays and contacts described for the ascending operation of the elevator.

It is, of course, possible to use in addition to the interlocking and safety device aforescribed, such additional interlocking devices as are common with modern elevator installations 130 but these form no part of the present invention.

It will be noted that in case of phase failure or phase reversal, the tube 1 is affected in the manner described in connection with Fig. 2 and the aforementioned co-pending application and 140 is under these conditions incapable of supplying any current to the various magnet circuits, so that no power is available for the operation of the controller and the elevator will therefore come to a stop and cannot be operated until 145 normal conditions of phase rotation and phase continuity are restored.

What we claim as new and desire to secure by Letters Patent is:

1. In combination, a polyphase supply circuit, 150

- a translating device, means responsive to variations in voltage, phase rotation and/or phase continuity of said supply, including an electron tube for establishing circuit connections between said supply circuit and said translating device, said tube having a control electrode, means to interrupt the circuit of said tube to thereby stop discharge through said tube and to reclose said circuit for reviving said discharge by said tube and means rendered effective by current supplied by said tube and acting on said control electrode to insure against discharge by said tube for a given minimum period following cessation of discharge thereby upon interruption of said circuit. 80
2. In combination, a polyphase supply circuit, a load circuit, a gaseous electron tube provided with a cathode and anode connected between said circuits and with a control electrode, means to complete connection of said circuits, means subjecting said electrode to a voltage which is derived from said supply circuit and which, under normal voltage and phase conditions in the latter circuit, lags a given angle behind the voltage impressed on said anode, said tube being thereby caused to discharge at the beginning of the positive half cycle of impressed voltage and the second mentioned means being sensitive to abnormal voltage and/or phase conditions to 95
- reduce said lag, a condenser and a discharge impedance associated with said control electrode, means to charge said condenser by a current passing through said tube to a potential capable of preventing starting of current flow through the tube for a given minimum period following cessation of discharge thereby upon interruption of current flow, means to discharge the condenser through said impedance upon such interruption and means to re-establish said connection at will. 100
3. In combination, a polyphase supply circuit, a load circuit, a gaseous electron tube provided with a cathode and anode connected between said circuits and with a control electrode, means to complete connection of said circuits, means subjecting said control electrode to a voltage which is derived from said supply circuit and which, under normal voltage and phase conditions in the latter circuit, lags a given angle behind the voltage impressed on said anode, said tube being thereby caused to discharge at the beginning of the positive half cycle of impressed voltage and the second mentioned means being sensitive to abnormal voltage and/or phase conditions to 105
- reduce said lag, a condenser and a discharge impedance associated with said control electrode, means to charge said condenser by a current passing through said tube to a potential capable of preventing starting of current flow through the tube for a given minimum period following cessation of discharge thereby upon interruption of current flow, means to discharge the condenser through said impedance upon such interruption and means to re-establish said connection at will. 110
4. In combination, a polyphase supply circuit, a translating device, a gaseous electron tube provided with a cathode and anode connected between said circuits, said tube being also provided with an electrode arranged to control the current transmitted therethrough, said electrode being connected to the supply circuit to be normally subjected to a potential which lags a given angle behind the anode potential, such lag being reduced by abnormal current and/or voltage conditions in the circuit, a condenser and a discharge impedance associated with said control electrode, means to charge said condenser by a current passing through said tube to a potential capable of preventing starting of current flow through the tube and means to interrupt the connection of said tube and to discharge the condenser through said impedance and to re-establish said connection at will. 115
5. In combination, a polyphase supply circuit, a translating device, a gaseous electron tube provided with a cathode and anode connected between said circuits, said tube being also provided with an electrode arranged to control the current transmitted therethrough, said electrode being connected to the supply circuit to be normally subjected to a potential which lags a given angle behind the anode potential, such lag being reduced by abnormal current and/or voltage conditions in the circuit, a condenser and a discharge impedance associated with said control electrode, means to charge said condenser by a current passing through said tube to a potential capable of preventing starting of current flow through the tube and means to interrupt the connection of said tube and to discharge the condenser through said impedance, the last mentioned means being controllable to 120
- reestablish said connection at will to revive the discharge of said tube subject to delay pending discharge of said condenser or alternatively to eliminate the delay due to the charge of said condenser. 125
6. In combination, a polyphase supply circuit, a motor, reversing means for connecting said motor to said supply circuit, means for controlling said reversing means, said latter means being responsive to variations in voltage, phase rotation and/or phase continuity of said supply circuit and including an electron tube having a control electrode, means to interrupt the circuit of said tube to thereby stop discharge through said tube and to reclose said circuit for 130
- reviving discharge by said tube and means rendered effective by current supplied by said tube and acting on said control electrode to insure against discharge by said tube and restarting of the motor for a given minimum period following cessation of discharge thereby upon interruption of said circuit. 135
7. In combination, a polyphase supply circuit, a motor, reversing means for connecting said motor to said supply circuit, means for controlling said reversing means, said latter means being responsive to variations in voltage, phase rotation and/or phase continuity of said supply circuit and including an electron tube having a control electrode, means to interrupt the circuit of said tube to thereby stop discharge through said tube and to reclose said circuit for reviving discharge by said tube, means rendered effective by current supplied by said tube and acting on said control electrode to insure against discharge by said tube and restarting of the motor for a given minimum period following cessation of discharge thereby upon interruption of said circuit, and means to eliminate at will the time delay of said last mentioned means. 140
8. In combination, an elevator, a polyphase current supply circuit, a motor for driving said elevator, reversing means for connecting said motor to said supply circuit, means for controlling said reversing means, the second men- 145
- 150

- tioned means being responsive to variations in voltage, phase rotation and/or phase continuity of said supply circuit and including an electron tube having a control electrode, means to interrupt the circuit of said tube to thereby stop discharge through said tube and to reclose said circuit for reviving discharge by said tube and means rendered effective by current supplied by said tube and acting on said control electrode to insure against discharge by said tube and restarting of the motor for a given minimum period following cessation of discharge thereby upon interruption of said circuit.
9. In combination, an elevator, a polyphase current supply circuit, a motor for driving said elevator, reversing means for connecting the motor to said supply circuit, means for controlling said reversing means, the second mentioned means being responsive to variations in voltage, phase rotation and/or phase continuity of said supply circuit and including an electron tube having a control electrode, means to interrupt the circuit of said tube to thereby stop discharge through said tube and to reclose said circuit for reviving discharge by said tube, means rendered effective by current supplied by said tube and acting on said control electrode to insure against discharge by said tube and restarting of the motor for a given minimum period following cessation of discharge thereby upon interruption of said circuit and means to eliminate at will the time delay of said last mentioned means.
10. In combination, an electron tube having a control electrode, a circuit supplied through said tube, means in series with said tube to interrupt said circuit and thereby stop the discharge through said tube and to reclose said circuit for reviving discharge by said tube and means rendered effective by current supplied by said tube and acting on said control electrode of said tube
- to insure against discharge by said tube for a given minimum period following cessation of discharge thereby upon interruption of said circuit.
11. In combination, a translating device, an electron tube in circuit therewith and having a control electrode, energy storage means associated with said tube, means to charge the former means by a current passing through said tube to a potential capable of preventing starting of current flow through said tube for a given time after interruption of said flow, and means in series with said tube to interrupt the circuit of said tube and to discharge said energy storage means and to reclose said circuit at will.
12. In combination, a translating device, a gaseous electron tube in circuit therewith and having a control electrode, a condenser and a discharge impedance associated with said tube, means to charge said condenser by a current passing through said tube to a potential capable of preventing starting of current flow through said tube for a given time after interruption of said flow, and means to interrupt the circuit of said tube and to discharge the condenser through said impedance and to reclose said circuit at will.
13. In combination, a translating device, a gaseous electron tube in circuit therewith and having a control electrode, a condenser and a discharge impedance associated with said tube, means to charge said condenser by a current passing through said tube to a potential capable of preventing starting of current flow through said tube, means to interrupt discharge of said tube and to discharge the condenser through said impedance and means to revive said discharge of said tube subject to delay pending discharge of said condenser or alternatively eliminate the delay due to the charge of said condenser.
